VALVE APPARATUS FOR PUMPING SYSTEMS

Irvin E. Litz, Denver, Colo.

Application December 16, 1938, Serial No. 246,089

2 Claims. (Cl. 277—44)

This invention relates to improvements in pumping apparatus and systems. It is particularly well adapted for pumping water in rural installations but obviously it may be used to pump any other liquid such as oil, brine, etc.

A principal object of the invention is to provide pumping apparatus and a system of pumping that uses the natural force of air currents or "wind" as the prime mover, the pumping being effected through the intermediary of compressed air.

Another object is the provision of such an apparatus and system whereby the wind-actuated mechanism may be installed either at or remote from the well or other source of the liquid to be pumped.

A further object is to provide novel mechanism for adjusting the wind-actuated mechanism to correspond with the direction of the wind at all times.

Still another object is to provide apparatus of this character that has novel means for selectively locking it against operation when so desired.

A still further object of the invention is to provide pumping apparatus and a system that is adaptable to raise water from wells of greatly different depths.

Still another object is to provide in apparatus and a system of this character, means for accumulating and automatically releasing wind-pumped compressed air to displace water or other liquid to be elevated or otherwise moved.

Other objects and advantages reside in details of design and construction which will be more fully disclosed in the following description and in the drawings wherein like parts have been similarly designated and in which:

Figure 1 is a fragmentary elevation, partially in section, of apparatus and a system that embodies the present invention;

Figure 2 is a fragmentary view, partially in section, of certain details of the apparatus and system illustrated in Figure 1;

Figure 3 is a fragmentary, sectional view on a larger scale, taken along the line 3—3 of Figure 1, illustrating certain details shown in Figure 1;

Figure 4 is a sectional view on a larger scale, illustrating certain details of the portion of the apparatus shown in Figure 2, and

Figure 5 is a fragmentary, sectional view of an optional modified detail of the apparatus.

In the drawings, reference character 12 denotes a tower which is preferably made of structural steel and triangular in cross section, but which

may be made in any suitable size or shape and of any preferred material. At the top the tower carries a wind-driven mechanism 13 which is adapted for rotary or swivel movement with reference to the tower, about a substantially vertical axis.

The wind-driven mechanism in the present illustrative example, comprises a hollow housing 14 which journals a hollow shaft 15 on which is mounted a wind-driven propeller 16 having a conventional governor mechanism 17. Opposite the propeller 16, the housing 14 carries an air compressor 18, which is in direct driven connection with the hollow shaft 15 through the intermediary of a stub shaft 19 splined into the shaft 15 as at 20.

A brake drum 21 is carried on the propeller and is positioned to be acted upon by internal brake shoes not shown in specific detail since their construction would be similar to any internal brake such as, for instance, that used on motor cars. The brake shoes are actuated by expanding mechanism of a well-known type such as an eccentric cam, which in turn is controlled by a brake rod 22 which is under manual control by another brake rod 22a through the intermediary of mechanism shown more specifically in Figure 3 and which will be later described in greater detail.

A fin or rudder 23 is suitably attached to the wind-driven mechanism 13 to keep the propeller 16 at all times directly facing the direction from which the wind is blowing. The entire wind-driven mechanism 13 is mounted upon suitable anti-friction bearings designated as a whole by reference character 24, the details of which are shown in Figure 3 and will be more fully described hereinbelow.

The discharge port of the compressor 18 is connected with a conduit 25, which connects through the arrangement shown in Figure 3, with conduit 25a, which is in air-conductive swivel connection with conduit 25b through the intermediary of a swivel joint 26. The swivel joint 26 is provided with a stop arm 27 which may contact a stop 28 as the wind-driven mechanism 13 swivels on its vertical axis.

Conduit 25b is connected with a flexible conductor such as a rubber hose 29, that in turn is in air-conductive connection with a conduit 30. The object of the flexible connection 29 is to permit a limited degree of relative swivel motion of the wind-driven mechanism 13 relative to the tower and the conduit 30 without relative swivel movement of the air-conductive conduits through the intermediary of the swivel joint 26. If the

said swivel movement of the mechanism 13 is of such an extent that the stop arm 27 contacts the stop 28, then the swivel joint 26 will function. The objects in such an arrangement include sparing the swivel joint 26 from excess wear by permitting a certain amount of relative swiveling through the intermediary of the flexible conductor 29, and further, when the mechanism 13 does swing enough to bring the stop arm 27 against the stop 28, the momentum will facilitate the swivel action of the swivel joint 26 which might have a tendency to stick and otherwise be difficult to move.

A constant take-up packing nut is shown at 31, which permits the brake rod 22a to extend therethrough without air leakage.

Referring to Figure 2, an accumulator valve is shown at 32, which valve is fully illustrated in Figure 4. Valve 32 is connected with conduit 30 and is intended to be located at the top of the well or adjacent any other supply of liquid to be pumped or moved. The object of the valve 32 is to accumulate and automatically release compressed air delivered therethrough from compressor 18, as will be hereinbelow fully set forth.

When a charge of accumulated compressed air is released from valve 32, it passes through conduit 33 which leads through a packing gland 34 down through pipe 35 to connect with a discharge jet 36, which is located within an air-tight cylinder 37 and which projects outwardly and laterally from the lower portion of the pipe 35. The bottom of the cylinder 37 is closed by an inwardly and upwardly opening check valve 38 and the bottom of the pipe 35 is similarly closed by another check valve 39.

Referring to Figure 3, an air-tight chamber 40 is carried on the anti-friction bearing assembly 24 and supports the hollow housing 14. Mounted within the chamber 40 is a lever arm 41 that is secured to the brake rod 22. The other brake rod 22a is connected with the lever arm 41 by means of a ball and socket joint 42. The conduit 25 leading to the compressor 18 is in conductive connection with the interior of the chamber 40 to which the conduit 25a is also connected.

The anti-friction bearing assembly 24 is suitably supported on structure 43, which in turn is supported on member 44 that is bolted or otherwise attached to the tower 12. This arrangement provides for a concentric connection between the brake rod 22a and the brake actuating rod 22 and also a concentric air-conductive connection with the interior of chamber 40 so that the entire wind-driven mechanism 13 may swivel with reference to the tower 12 as hereinabove set forth.

Referring to Figure 4, the details of automatic accumulator valve 32 are illustrated. This valve comprises a chamber 45 which is in conductive communication with the air-conductive conduit 30 which leads from the compressor 18. Above chamber 45 is a second chamber 46 which is connected therewith by means of a port 47 that is controlled by a valve 48 carried on a valve stem 49 provided with a compression spring 50.

A yoke 51 is secured to a piston 52 that is in sealed engagement with the inner walls of the chamber 45 by means of a sealing cup 53. A body of liquid 54 is in the chamber 45 below the piston 52, and a port 55 connects the liquid-holding portion of the chamber 45, with a reservoir 56. The port 55 is under manual control by means of a needle valve assembly designated as a whole by reference character 57. The liquid 54 is prefer-

ably oil, glycerine, or the like, that is not subject to freezing.

The chamber 46 is in conductive connection with the conduit 33. Valve stem 49 extends upwardly through the port 47 and carries a yoke 58 which terminates in a guide stem 59 which is housed in the head 60 of the upper chamber 46. The position of the guide stem 59 is under manual control by means of a hand-nut 61 that is operable on a screw 62 in opposition to a compression spring 63. The yoke 58 carries a second valve 64 that controls a port 65 that is in communication with the open atmosphere at 66.

Operation

In this example of a reduction to practice of the present inventive concept, the wind-driven propeller 16 operates the compressor 18 to deliver compressed air through conduits 25, 25a, 25b, 29 and 30, to the automatic accumulator valve 32. Thus compressed air accumulates in chamber 45 of said accumulator valve and as the pressure builds up in this chamber, piston 52 together with yoke 51, are forced downwardly, compressing spring 50 on the valve stem 49 and forcing some of the liquid 54 past the needle valve 57 out through port 55 into reservoir 56. As the compression of spring 50 advances, the valve 48 will be opened with a quick action when the pull thereon overcomes the pneumatic pressure thereagainst. However, the compressive and expansive action of the air in chamber 45 is such that compression spring 50 may be omitted if desired. Since the square area of the piston 52 is greater than that of the valve 48, a differential will be built up which will effect the sudden opening of the valve 48. The quick opening movement of the valve will be further accentuated and facilitated by the expansion of the compressed spring 50.

When the sudden opening of the valve 48 occurs, air accumulated under pressure in chamber 45 will pass through port 47 and along conduit 33 through discharge jet 36 into cylinder 37. The cylinder 37 is immersed in the water of the well or any other liquid to be pumped, and since check valve 38 opens inwardly and upwardly, the cylinder 37 will be substantially filled with the liquid. When the compressed air is discharged into the cylinder 37, it will displace the body of liquid therein, which will then be forced upwardly through check valve 39 thence upwardly along pipe 35 and be discharged through discharge line 35a.

The downward movement of the valve 48 together with its stem 49, will move yoke 58 downwardly to close valve 64 on its seat 65, thus closing passage 66. As the accumulated air is released from chamber 45 through port 47 and conduit 33, the entire valve mechanism will be raised by the action of the compression spring 63 since the pneumatic pressure in chamber 45 has been reduced. This will again close valve 48 and open valve 64. In this latter position, chamber 46 is open to the atmosphere through exhaust port 66, which permits water or other liquid being pumped, to again refill cylinder 37 because atmospheric pressure is restored therein.

The rate of ejection of the liquid 54 from the chamber 45 beneath piston 52 into reservoir 56, may be optionally governed by the adjustment of the needle valve 57, i. e., outward flowing of said hydraulic fluid 54 past needle valve 57 during the downward stroke of piston 52, and the inward flow of said fluid on the upward stroke of

said piston, controls the time of discharge of compressed air into cylinder 37 and also the period of exhaustion of air to atmosphere through port 66, necessary to refill said cylinder, 37, with water, or other pumped liquid.

Valve 64 is loosely held in the yoke 58 so that it is certain to seat properly at 65. The compressive force of spring 63 is optionally adjustable by means of the hand-nut 61 and this nut 61 together with needle valve 57, constitute the control factors in governing the operation of the automatic accumulator 32.

An operator may apply braking action to the brake drum 21 on the propeller to stop the latter from operation, by moving the manually operable brake rod 22a. By this arrangement, the entire apparatus and system may be started or stopped at the will of the user.

When circumstances are such that the cylinder 37 is well submersed in the water of a well or the like, and where the relationship of the lift to the depth of submersion of the cylinder is favorable, the automatic accumulator valve 32 may be omitted and the compressed air output from the compressor 18 may be conducted through the various conduits into the cylinder 37, which will then operate similar to the "air lift." This will result in an intermittent discharge of water from the well without the use of an accumulator valve.

The modern type two-blade propeller of the character developed for airplanes, as illustrated at 16, Figure 1, will develop sufficient revolutions per minute under normal wind conditions, to permit the direct drive connection between the propeller and the compressor 18. In the old fashion fan type windmill, the wind-actuated wheel will not ordinarily develop sufficient speed for direct connection to a compressor.

In Figure 5, an automatic clutch is illustrated as an optional modification of the connection between the shaft 15a that carries the propeller and the stub shaft 19a that is directly connected with the compressor. Under some circumstances, this clutch may be desirable because it provides automatic means for completely unloading the propeller between operations thereof, so that a very small wind velocity will start the propeller to rotate, which rotation will be accelerated and the clutch will then be automatically engaged to start the compressor. Under these circumstances, the necessary propeller torque is reached and in addition, the momentum of the propeller aids in overcoming the static inertia of the compressor, making for a more ready pick-up start of said compressor.

A preferred form of automatic clutch comprises a jaw clutch member 70 having an annular beveled portion 71 and a screw thread 72 which has a relatively fast lead angle. The screw 72 engages in a correspondingly threaded female screw in the end of the shaft 15a. The shaft 15a carries a plurality of bifurcated lugs 73, in each of which is pivotally mounted a centrifugal weight 74 that terminates adjacent the bevel 71 in a cam-like clutch-engaging end 75. As the propeller and its shaft 15a which is carried in suitable bearings not shown in Figure 5, begin to rotate by means of air currents, the pivoted weights 74 will be thrown outwardly from the shaft by centrifugal force, which action will bring the cam-like ends thereof, 75, in sliding engagement with the bevel 71 of the clutch element 70 thus forcing the clutch member 70 outwardly away from the end of the shaft 15a so

that it will contact another jaw clutch member 76 which is keyed onto the shaft 19a.

As this contact occurs, there will be relative rotary movement between the shaft 15a and the fast lead screw 72, which in the instant illustration, is left-hand. This relative movement will screw the clutch member 70 into deep meshing engagement with the other clutch member 76, where it will be so held to transmit driving torque to the shaft 19a and the compressor 18 as long as there is an input of driving force from the propeller 16.

When the wind currents subside and the power input ceases, a compression spring 77 will separate the clutch members 76 and 70 by screwing the latter back into the end of the shaft 15a. It will be understood that the relative angle of the screw 72 is such that longitudinal force thereon will produce relative turning movement thereof in its threaded socket.

It will thus be seen that the apparatus and system herein illustrated and described may be used to elevate or pump water or any liquid and that since the intermediary of the compressed air is so extremely flexible, the wind-driven mechanism may be located at a distance from the well or other source of liquid as, for instance, the tower and wind-driven mechanism may be on a hill while the well is in a valley or other depression in the contour of the earth's surface.

The apparatus and system herein set forth is capable of effecting the stated objects of this invention, and while this specification discloses preferred means for reducing the present invention to practice and a preferred embodiment of the invention, changes may occur to those skilled in the art and may be made within the scope of the appended claims, without departing from this inventive concept.

For purposes of simplified terminology in the appended claims, upper chamber 46, Figure 4, will be designated as the exhaust chamber, and the space 45 immediately above the piston 52 will be designated as the accumulating chamber and the space immediately below piston 52 in which is yieldingly confined the body of liquid 54, will be set forth as the escapement chamber.

What I claim and desire to secure by Letters Patent is:

1. An intermittently operable accumulator comprising an accumulating chamber inclusive of means suitable for connecting said chamber with a source of gas under pressure and inclusive of an exhaust port, an escapement chamber, a piston operable in said chambers and positioned to separate them, a spring-closed valve positioned at said exhaust port to govern the flow of fluid from the accumulating chamber, spring means connecting the piston with the valve whereby said valve is opened by movement of the piston away therefrom, and a body of liquid having limited escapement yieldingly confined in said escapement chamber in a position to be pressed by said piston when the piston is acted upon by accumulating gas under pressure in said accumulating chamber whereby movement of the piston under the influence of accumulating gas is retarded.

2. An intermittently operable accumulator comprising an accumulating chamber inclusive of means suitable for connection with a source of gas under pressure and inclusive of an exhaust port, an exhaust chamber inclusive of a vent positioned to receive gas discharged through said port, an escapement chamber, a piston operable

in said accumulating chamber and said escapement chamber and movably separating the two chambers, a spring-closed valve positioned at said exhaust port to govern the flow of fluid therethrough, spring means connecting the piston with the valve whereby said valve is opened by movement of the piston away therefrom, a valve in the exhaust chamber positioned to open and close said vent and connected with the first

5 said valve for actuation thereby, and a body of liquid having a limited escapement yieldingly confined in said escapement chamber in a position to be pressed by movement of said piston when acted upon by accumulating gas under pressure in the accumulating chamber whereby such pressing movement of the piston is retarded.

IRVIN E. LITZ.
